DAVID W. DORRANCE, OF SAN JOSE, CALIFORNIA

LOCK JOINT FOR ARTIFICIAL HANDS

Application filed May 22, 1930. Serial No. 454,617.

The object of the invention is to provide an artificial hand comprising complementary fingers which are positively locked against further opening movement than that to which they are adjusted as when they are caused to grip on a tool or to engage the handle of some device to be carried; to provide a lock of this nature which will function with the movement of the fingers in the infinitesimal increments; to provide for the automatic release of the lock by the means effecting the normal opening movement or operation of the fingers; to provide means for manual operation by which the release or setting of the locking means may be accomplished independently of the means provided for the automatic functioning of this feature; to provide a construction which will make for the free relative swinging movement of the fingers; and to provide a construction of the character described which is generally of simple form and susceptible of comparatively cheap manufacture and low marketing cost.

With this object in view the invention consists in a construction and combination of parts of which a preferred embodiment is illustrated in the accompanying drawings, wherein:

Figure 1 is a side elevational view of an artificial hand embodying the invention.

Figure 2 is an elevational view looking from a direction at right angles from that from which Figure 1 is viewed.

Figure 3 is a view similar to Figure 1 but looking at the reverse side of the latter.

Figure 4 is a view on an enlarged scale and partly in section, and illustrating the lock comprised in the invention, the parts being illustrated in the positions assumed when the fingers are in closed position.

Figure 5 is a view similar to Figure 4, the fingers being shown in partial open position.

Figure 6 is a view similar to Figure 4 with the full open position of the fingers being indicated.

Figure 7 is a perspective view illustrating the rock shaft constituting the locking element.

Figure 8 is a detail perspective view illus-

trating the eye and adjacent parts of the pivoted fingers.

Figure 9 is a detail sectional view on the plane indicated by the line 9—9 of Figure 2.

The fingers 10 and 11 are connected for relative movement, the former being formed with a base or body portion 12 which at its lower end is provided with a coupling 14 designed for detachably connecting it with a stump member.

The body portion 12 is formed with a tapped eye for the reception of the screw 15 of which the shouldered portion 16 passes through an eye 17 in the finger 11, the shouldered portion constituting a journal for said finger 11 so as to pivotally mount it on the body portion of the finger 10.

Ball bearings 18 are interposed between the adjacent sides of the eye portion of the finger 11 and the body portion of the finger 10, being carried in grooves formed in the two which provide a ball race, so that the balls may provide for ready swinging movement of the finger 11 with reference to the finger 10.

Rotatably mounted in the body portion 12 with its axis parallel to the axis of the screw 15 is a rock shaft 19, this rock shaft being reduced between its ends as indicated at 20 to provide an eccentric portion which is moved toward or away from the periphery of the eye portion 17, when the rock shaft is rotated. A section of the periphery of the eye portion 17, as indicated at 21, is shaped to a curve of gradually reduced radius forming a cam and as the pivoted finger 11 is moved from closed to open position, the cam traverses the eccentric portion 20 from the lowest point of the former to the highest, if the position of the eccentric portion is such as to permit free passage of the cam.

The rock shaft 19, at one end, is formed with the spaced flanges 22 and in the space between these flanges is received the coil spring 23 which is terminally connected to the shaft by means of its inturned extremity 24 engaging a diametrical hole 25 in the shaft, the remaining terminal of the spring being anchored to the body portion 12 by means of the screw 26. The tendency of the

spring is to rotate the rock shaft so as to dispose the eccentric portion against the cam 21 and whatever the relative positions of the two fingers 10 and 11, any tendency to shift the pivoted finger 11 to further open position by a force applied to the finger, results in a tendency to rotate the rock shaft by the pressure of the cam upon the eccentric portion 21 and this against the turning force of the spring. Since the turning force applied to the rock shaft under such conditions is almost directly radial, the eccentric portion acts as a positive lock to the pivoted finger 11 against further opening movement. Thus if the fingers be separated and closed upon an interposed object, practically no force applied by that object tending to effect further open position will result in further separation of the fingers.

20 The fingers are normally yieldingly impelled towards closed position by the members 27 which are preferably elastic bands slipped over the fingers and positioned between the foldable thumb hook 28 on the finger 11 and the arm 29 carried by the latter.

At the extremities of the arm 29 there is pivotally mounted as by means of a screw 30, the lever 31, the latter having an eye 32 for the attachment thereto of a pull cord 30 and at the end remote from the eye having a pivotal connection with a link 33 which latter is pivotally connected at an intermediate point with an arm 34 whose one end is seated in the slot 35 of the rock shaft 19 and secured to the latter by a fastener 36. That end of the arm 34 remote from the fastener 36 constitutes a single manipulating terminal 37 by means of which the rock shaft may be actuated independently of the means normally provided for its actuation and the separation of the fingers 10 and 11.

In the use of the invention, the user is provided with a harness for attachment to the body at some point with a pull cord extending preferably through the sleeve and terminally connected with the eye 32. By this means he may exert a pull on the pull cord which then rocks the lever 31 which in turn rocks the rock shaft 19 through the instrumentality of the link 33 and arm 34, thus swinging the eccentric portion 20 away from the cam 21, the continued pull then resulting in swinging the finger 11 away from the finger 10 for the placement of an object or tool to be inserted therebetween. On release of the pull on the pull cord, the two fingers 10 and 11 are engaged with the interposed object and, since the spring 23 has restored the normal position of the rock shaft, its eccentric portion 20 is in obstructing relation to the cam 21, and backward swinging or opening movement of the finger 11 is precluded.

The rock shaft actuating terminal 37 is provided for rocking the rock shaft in the same manner as would be accomplished

through the link 33, but only in case of any sticking or binding between the cam and eccentric portion 20. Conversely, the spring 23 failing to shift the eccentric portion 20 back into engagement with the cam after having once been separated therefrom, pressure on the terminal 37 of the arm 34 will suffice to accomplish this.

The invention having been described what is claimed as new and useful is:

1. An artificial hand comprising pivotally connected fingers yieldingly impelled towards each other, and a rocking device carried by the one and engageable with the other, said rocking device comprising a rock shaft having an eccentric portion, the finger engaged thereby having a cam contacting with said eccentric portion, and a spring tending to rotate the rock shaft to move the eccentric portion towards said cam.

2. An artificial hand comprising pivotally connected fingers yieldingly impelled towards each other, and a rocking device carried by the one and engageable with the other, said rocking device comprising a rock shaft having an eccentric portion, the finger engaged thereby having a cam contacting with said eccentric portion, and a spring tending to rotate the rock shaft to move the eccentric portion towards said cam, the cam carrying finger having means for attachment to a pull cord and operative connections between said means and the rock shaft to effect rotation of the latter in opposition to said spring and in advance of applying a pull on said finger.

3. An artificial hand comprising pivotally connected fingers yieldingly impelled towards each other, and a rocking device carried by the one and engageable with the other, said rocking device comprising a rock shaft having an eccentric portion, the finger engaged thereby having a cam contacting with said eccentric portion, and a spring tending to rotate the rock shaft to move the eccentric portion towards said cam, the cam carrying finger having means for attachment to a pull cord and operative connections between said means and the rock shaft to effect rotation of the latter in opposition to said spring and in advance of applying a pull on said finger, the pull cord attaching means consisting of a lever pivotally mounted on said finger and said operative connection comprising an arm carried by the rock shaft and a link pivotally connecting said lever and said arm.

4. An artificial hand comprising pivotally connected fingers yieldingly impelled towards each other, and a rocking device carried by the one and engageable with the other, said rocking device comprising a rock shaft having an eccentric portion, the finger engaged thereby having a cam contacting with said eccentric portion, and a spring tending to rotate the rock shaft to move the eccentric

portion towards said cam, the cam carrying finger having means for attachment to a pull cord and operative connections between said means and the rock shaft to effect rotation of the latter in opposition to said spring and in advance of applying a pull on said finger, the pull cord attaching means consisting of a lever pivotally mounted on said finger and said operative connection comprising an arm carried by the rock shaft and a link pivotally connecting said lever and said arm, said arm, beyond the pivotal connection with said link being provided with a single terminal for the independent actuation of the rock shaft.

5. An artificial hand comprising pivotally connected fingers yieldingly impelled towards each other, the one being formed with a cam, a rock shaft rotatably mounted in the other and having an eccentric portion engageable with the cam when the rock shaft is rotated in one direction and separated from the cam when the rock shaft is rotated in the opposite direction, a spring tending 10 to rotate the shaft in a direction to engage the cam and eccentric portion of the rock shaft, pull cord actuated means for rotating the rock shaft in a direction opposite to that effected by the spring, said means having an 15 element carried by the cam carrying finger so as to subsequently effect movement of that finger with reference to the other finger.

6. An artificial hand comprising pivotally connected fingers yieldingly impelled towards each other, the one being formed with a cam, a rock shaft rotatably mounted in the other and having an eccentric portion engageable with the cam when the rock shaft is rotated in one direction and separated from 20 the cam when the rock shaft is rotated in the opposite direction, a spring tending to rotate the shaft in a direction to engage the cam and eccentric portion of the rock shaft, pull cord actuated means for rotating the rock shaft in 25 a direction opposite to that effected by the spring, said means having an element carried by the cam carrying finger so as to subsequently effect movement of that finger with reference to the other finger, and means for 30 manually actuating the rock shaft independently of the pull cord means.

In testimony whereof he affixes his signature.

DAVID W. DORRANCE.
